HIRAM BRUCE SNYDER, OF FULLERTON, CALIFORNIA.

METHOD AND APPARATUS FOR PRODUCING A CHEMICAL UNION BETWEEN HYDRO-CARBON GASES AND HYDROCARBON OILS.

Application filed December 27, 1921. Serial No. 524,973.

To all whom it may concern:

Be it known that I, HIRAM B. SNYDER, a citizen of the United States, and a resident of Fullerton, in the county of Orange and State of California, have invented certain new and useful Improvements in Methods and Apparatus for Producing a Chemical Union Between Hydrocarbon Gases and Hydrocarbon Oils, of which the following is 10 a specification.

This invention relates to a method and apparatus for producing a chemical union between methane gases and heavy hydrocarbon oils.

15 The object of the invention is to provide an apparatus by which a complete union between natural or methane gases CH_4 and heavy hydro-carbon such as $\text{C}_{15}\text{H}_{32}$ may be had, and thereby producing hydro-carbon 20 compounds such as C_8H_{18} , or other hydro-carbon compounds of a different chemical structure depending upon the hydro-carbon oil united with the methane gases.

In carrying out the present invention it 25 is contemplated to place a certain volume of natural gas under compression, and at a predetermined period of compression to introduce a certain volume of heavy hydro-carbon oil into the gas, and then continue the 30 compressing of the gas until it is bordering its liquid state. At this period the molecules of the co-mingled gas and oil are disrupted and broken up by the passage of an electrical arc therethrough, after which the atoms of 35 the gas and oil may re-assemble into a new chemical compound having a different chemical structure, and it is then discharged from the compression chamber.

The invention is illustrated by way of example in the accompanying drawings, in 40 which:

Figure 1 is a diagrammatic view illustrating the preferred form of the invention with parts thereof shown in cross section to more 45 clearly illustrate the invention,

Figure 2 is a modified form of apparatus suitable for accomplishing the purposes of the invention.

Referring to the drawings in detail, and 50 particularly to Figure 1, 10 indicates a cylinder which is elongated as shown and having fitted therein a piston or plunger 11. The inner end of the cylinder is enlarged as at 12 and adapted to accommodate the

packing gland 13. The outer end of the 55 cylinder 10 is also enlarged as at 14 and provided with a relatively thick head closure 15 in which there is mounted a pair of electrodes 16, said electrodes being suitably insulated from the head as indicated at 17 60 and having their outer ends connected with the terminals of the secondary transformer coil 18, as shown. The primer coil 19 is connected with a low voltage source and the secondary coil 18 is adapted to produce a relatively high voltage for the electrodes 16, as for example, the source of supply may be 65 110 volts, while the secondary coil of the transformer produces 50,000 volts.

The inner ends of the electrodes projecting 70 into a hemispherically shaped recess 20 formed in the inner side of the head 15, and likewise register with a similar recess 21 formed in the forward end of the piston 11. Also in the head 15 of the cylinder 10 there is 75 positioned a pair of tappet valves 22 and 23, the stem of each valve being encircled by a compression spring 24 which is adapted for holding the valves closed. With the opening controlled by the valve 23 there communicates 80 an eduction pipe 25 through which the methane gases are introduced into the cylinder, and with the opening controlled by the valve 22 there communicates a pipe 26 which may be suitably connected to a container or tank in which the liquid coming 85 through said pipe 26 may be collected. The valve 22 may be operated by a bell crank lever 27 which may be actuated by a suitable cam 28 through the rod 29.

90 For introducing the heavy oils into the cylinder 10, I provide an oil pump which comprises a cylinder 30 which communicates at its lower end with the cylinder 10 through an orifice 31. On the one side of the cylinder 95 30 there is formed a tubular extension 32 which terminates near its outer end in an enlargement 33, said enlargement being hollow as shown, and communicating with a tubular projection 34, which may be attached to a 10 source of supply of heavy oil. A ball valve as indicated at 35 may be positioned in the enlargement 33 to regulate the flow of the oil into the cylinder 30. Within the cylinder 30 there is fitted a plunger or piston 36 which has formed at its upper end a slotted cross head 37. A disk or wheel 38 may be 10 suitably mounted with relation to the plun-

ger 36 so that a pin 39 carried by said disk may engage in the slot of the head 37 and operate the plunger 36 for pumping the oil through the orifice 31 into the cylinder 10.

5 In the operation of the present device, as heretofore described, a certain quantity of methane or natural gas is allowed to enter the cylinder 10 through the valve 23. The piston 11 is then made to commence its 0 compression stroke, and previous to its passing the orifice 31, the piston 36 will descend for injecting into the cylinder 10 a certain quantity of heavy hydro-carbon oil. Due to the fact that the orifice 31 restricts the 5 passage of said oil when being injected into the cylinder 10, the same will enter the cylinder in the form of a spray. The piston 11 will of course proceed in its compression stroke and when it has reached the 0 end thereof, the gas and heavy oil will be thoroughly mixed and in a co-mingled state. Also the oil and gas will be considerably heated due to the pressure to which it is subjected. The compression force of the 5 piston 11 is preferably so that at the completion of its stroke the gas is bordering its liquid state, and at this period a spark is caused to jump between the inner ends of the electrodes 16, which as is obvious, passes 0 through the body of compressed gas and oil. When this occurs the molecules of the oil and gas are entirely disrupted or broken up so that when the pressure is relieved they 5 will form themselves into new compounds of hydro-carbon oils. Also at the time when the piston 11 is started upon its return stroke the valve 22 is operated in order to permit the new compound of hydro-carbon oil formed to flow from the cylinder 10, through the pipe 26.

Referring to Figure 2 in which I have shown a modified form of the apparatus for carrying out my invention, 40 indicates a cylinder which is vertically disposed as shown and terminating at its lower end in a conical head portion 41 which is formed centrally thereof with a boss 42, said boss having a bore extending therethrough and a valve 43 seated in the upper end thereof adapted to form a closure therefor. Also the boss may be provided with a cap 44 and the stem 45 of the valve 43 encircled by a compression spring 46 which may be adapted to normally hold the valve in closed position. Also there may be threaded or otherwise extended through the boss 42 an education pipe 47. In the head portion 41 there is likewise provided a pair of electrodes 48, which may be suitably connected to the secondary of the transformer, as illustrated in Figure 1. Furthermore the head portion 41 of the cylinder 40 may have extended therethrough a pair of nozzle members as indicated at 49, and said nozzles suitably connected with a pipe and valve means

through which heavy hydro-carbon oil may be injected into the cylinder at the required intervals.

Within the cylinder there may be positioned a piston 49 which may be provided with the usual packing rings 50. Also in the side wall of the cylinder 40 there may be suitably mounted a valve 51, said valve having its stem 52 encircled by a compression spring 53 which is adapted to hold the valve in its closed position. Also the head of the valve may be rounded as at 54 so that upon the descent of the piston 51 the valve member will be unseated and permit gases to enter the cylinder, said gases being delivered within the casing 55 surrounding the valve member through means, not shown.

The operation of the form of my apparatus shown in Figure 2 is substantially the same as that shown in Figure 1. As the piston 49 descends the valve 51 is operated to permit a certain volume of methane gas or natural gas CH_4 , to enter the cylinder 40, and when the piston has reached a predetermined point in its compression stroke suitable valves may be operated for injecting into the cylinder 40 a certain amount of a heavy hydro-carbon oil, such as $\text{C}_{15}\text{H}_{32}$. The compression stroke of the piston 50 will of course continue and when it has reached the completion thereof, an arc may be caused to pass between the electrodes 48 which will disrupt and break up the molecules of the co-mingled gas and heavy oil. The same re-assembling of the atoms will again occur as described in the case of Figure 1, and a new hydro-carbon oil compound will be formed, such as C_8H_{18} . The valve 43 may then be operated for permitting this new compound to escape from the cylinder.

I claim:

1. The method of uniting gases of the methane series with hydro-carbon oils which consists in subjecting a volume of methane gas to a high degree of compression, then introducing a quantity of hydro-carbon oil into said compressed gas, and then passing an electrical arc through said gas and oil while in its co-mingled and compressed state.

2. The method of uniting gases of the methane series with hydro-carbon oils which consists in compressing a volume of methane gas to a predetermined degree, then introducing a quantity of hydro-carbon oil in the said compressed gas, then continuing the compression of said gas and oil until the gas borders its liquid state, and then discharging an electrical arc through said co-mingled oil and gas.

3. The method of chemically uniting gases of the methane series with hydro-carbon oils, which consists in compressing a vol-

ume of methane gas to a predetermined degree, then introducing a quantity of hydro-carbon oil into said compressed gas in the form of a spray, then continuing the compression of said gas and oil until the gas borders the state of a liquid, and then discharging an electrical arc through said mingled and compressed oil and gas.

4. In an apparatus of the character described, a compression cylinder and piston, means for introducing a gas into said cylinder previous to the compression stroke of said piston, means for injecting oil into said cylinder during the compression stroke of said piston, and means for passing an electrical arc through the oil and gas while compressed.

5. In an apparatus of the character described, a compression cylinder and piston, means for introducing a gas in said cylinder previous to the compression stroke of said piston, means for injecting oil into said cylinder during the compression stroke of said piston, and means for passing an electrical arc through the oil and gas while compressed, an eduction passage from said cylinder, and valve means for opening said passage after the currents of said arc.

6. In an apparatus of the character described, a compression cylinder, a piston operating therein, means for introducing a gas into said cylinder previous to the beginning of the compression stroke of said piston, means for injecting a quantity of heavy oil in the form of a spray into said cylinder during compression, and means for passing an electric arc through the oil and gas when compressed.

7. In an apparatus of the character described, a cylinder having its one end closed, and a piston operable therein for compress-

ing upon its stroke toward the closed end of the cylinder, valve means for introducing gas into said cylinder previous to the compression stroke of the piston, a combined pump and valve means for introducing heavy oil into said cylinder during the compression stroke of said piston, a pair of electrodes extending into the cylinder, and electrical connecting means whereby the arc may be caused between said electrode at the time when the piston has completed its compression stroke.

8. In an apparatus of the character described, a compression cylinder, a piston operable therein, valve means for introducing a gas into said cylinder previous to the beginning of the compression stroke of said piston, means for injecting oil into said cylinder during compression in the form of a spray, and means for passing an electrical arc through the oils and gas when said piston has completed its compression stroke.

9. The method of uniting a hydro carbon gas and a hydro carbon liquid which consists in subjecting a volume of hydro carbon gas to a high degree of compression then introducing a quantity of hydro carbon liquid into said gas, then passing an electric arc through said gas and liquid while in their comingled and compressed state.

10. The method of uniting a hydro carbon gas and a hydro carbon liquid which consists in subjecting a volume of hydro carbon gas to a high degree of compression then introducing a quantity of hydro carbon liquid into said gas in the form of a spray, then passing an electric arc through said gas and liquid while in their comingled and compressed state.

HIRAM BRUCE SNYDER.
